UNITED STATES PATENT OFFICE.

OTTO C. TRAUTMANN, OF NEW YORK, N. Y., ASSIGNOR TO SIDIO COMPANY OF AMERICA, INC., OF NEW YORK, N. Y., A CORPORATION OF NEW YORK.

PROCESS OF PRODUCING ARTICLES OF QUARTZ GLASS.

1,215,433.

Specification of Letters Patent.

Patented Feb. 13, 1917.

Application filed August 10, 1916. Serial No. 114,105.

To all whom it may concern:

Be it known that I, OTTO C. TRAUTMANN, a citizen of the United States, and a resident of New York city, in the county of 5 New York and State of New York, have invented certain new and useful Improvements in Processes of Producing Articles of Quartz Glass, of which the following is a specification.

10 This invention relates to processes of producing articles of quartz glass, particularly quartz glass vessels.

In producing a quartz glass vessel, it has hitherto been necessary to introduce a blast 15 of air into the interior of the plastic quartz body before it has had a chance to cool. This required the introduction of pipes and apparatus in the interior of the furnace which is impractical, due to the extreme 20 heat.

The present invention has for its object to devise a process whereby the vessel may be blown without any special apparatus and without requiring any handling, involving 25 loss of time. In the production of quartz glass bodies, the time element is very important for the reason that the plastic can be worked only within a small range of temperature, as will be understood by those 30 skilled in the art.

In the accompanying drawing illustrating diagrammatically one form of apparatus for carrying on my improved process,

Figure 1 is a sectional elevation of a furnace showing the plastic formed around the resistance core.

Fig. 2 is a section taken along line 2—2 of Fig. 1.

Fig. 3 is a sectional elevation of the furnace with the resistance core broken and the mold closed.

Fig. 4 is a section taken along line 4—4 of Fig. 3.

In carrying out my improved process, the 45 quartz is first fused in an electric furnace consisting preferably of a shell 10 lined with suitable heat resisting material 11. The base of the furnace is closed by a conductor 12 and at the top of the furnace is a conducting head 13 between which is positioned the resistance core 14. The latter is reduced in section at the intermediate ends thereof as at 15 for the purpose hereinafter set forth. Suitable devices as set screws 16 hold 55 the core in place.

The quartz sand is introduced into the furnace, the resistance core is properly clamped in place and the current turned on. The plastic mass of quartz 17 soon forms about the core. When the requisite amount 60 of plastic is formed, a door 18 at the bottom of the furnace is opened, permitting the surplus sand to escape. Thereupon the two movable parts 19 and 20, having a suitable concavity 21, 22, are actuated by any suitable 65 means as by levers 23 and rods 24. The concaved portions 21, 22 form a mold about the plastic as illustrated in Figs. 3 and 4.

It is now necessary to produce an interior pressure so as to expand the plastic into the 70 mold. This is accomplished as follows:

The upper portion of the resistance core 14 may be twisted or strain otherwise applied thereto, as by means of the tongs 25, so as to break the core at the weakened portion 15. The portions of the core may then be separated slightly, forming an arc 26, as clearly appears in Fig. 3. The gases generated by the arc then produce a pressure sufficient to force the plastic into the mold, 80 as will be readily understood.

The entire manipulation requires very little time, and during the entire period, the current may be continued so that the plastic mass is kept up to the proper temperature 85 at which it can be readily shaped.

Having thus described my invention, I claim as new and desire to secure by Letters Patent:

1. The process of forming quartz glass 90 vessels consisting in fusing the quartz material in an electric resistance furnace and then transforming the resistance furnace into an arc furnace whereby gases are generated by the arc to form a pressure to expand the plastic into a mold.

2. The process of forming quartz glass vessels consisting in heating quartz material in a resistance furnace to form a plastic mass about the resistance core, removing the 100 unfused quartz material, and then transforming the resistance furnace into an arc furnace whereby gases are generated by the arc to form a pressure to expand the plastic into a mold.

3. The process of forming quartz glass vessels consisting in heating quartz material in a resistance furnace to form a plastic mass about the resistance core, removing the 110 unfused quartz material, positioning a mold

about the plastic, and then transforming the resistance furnace into an arc furnace whereby gases are generated by the arc to form a pressure to expand the plastic into the mold.

- 5 4. The process of forming quartz glass vessels consisting in fusing the quartz material in an electric resistance furnace around a resistance core, applying a stress upon the resistance core so as to break the same into two portions and drawing the portions out into an arc to generate gases to create a pressure in the interior of the plastic body.
- 6 5. The process of forming quartz glass vessels consisting in fusing the quartz mate-

rial in an electric resistance furnace around 15 a resistance core, applying torsion upon the resistance core so as to break the same into two portions and drawing the portions out into an arc to generate gases to create a pressure in the interior of the plastic body.

Signed at New York city, in the county of New York and State of New York, July, 20 A. D. 1916.

OTTO C. TRAUTMANN.
